(57) **CLAIM**

The ornamental design for a vanity table, as shown and described.

DESCRIPTION

FIG. 1 is a front, right, top perspective view of a vanity table, showing my new design;

FIG. 2 is a rear, left, bottom perspective view of the reduced scale thereof;

FIG. 3 is a front elevational view of the enlarged scale thereof;

FIG. 4 is a rear elevational view of the enlarged scale thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof; and,

FIG. 9 is an enlarged view of detail 9 in FIG. 5.

The dashed broken lines in the figures are for the purposes of illustrating portions of the vanity table and form no part of the claimed design.

The short-short-long dashed broken lines immediately adjacent to the claimed areas in the views represent the boundaries of the design and form no part of the claimed design. The dash-dot-dash broken lines are for notating enlarged views and form no part of the claimed design.
